C. M. WILKINS

PULLER

Filed March 9, 1925

Charles M. Wilkins

INVENTOR

BY Victor J. Evans

ATTORNEY

Leo Hayes

WITNESS:

UNITED STATES PATENT OFFICE.

CHARLES M. WILKINS, OF SMITHFIELD, PENNSYLVANIA.

PULLER.

Application filed March 9, 1925. Serial No. 14,158.

To all whom it may concern:

Be it known that I, CHARLES M. WILKINS, a citizen of the United States, residing at Smithfield, in the county of Fayette and 5 State of Pennsylvania, have invented new and useful Improvements in Pullers, of which the following is a specification.

This invention relates to a puller for pulling sleeves from shafts and the like, the 10 general object of the invention being to provide a supporting member having a movable member therein which carries a projection for engaging a hole in a sleeve with means for causing the projection to engage the 15 hole when the puller is placed in the sleeve so that the sleeve will be contracted and pulled from the shaft by a turning and pulling movement of the puller.

Another object of the invention is to provide 20 means for locking the projection in the hole in the sleeve when necessary.

This invention also consists in certain other features of construction and in the 25 combination and arrangement of the several parts, to be hereinafter fully described, illustrated in the accompanying drawings and specifically pointed out in the appended claims.

In describing my invention in detail, reference 30 will be had to the accompanying drawings wherein like characters denote like or corresponding parts throughout the several views, and in which:

Figure 1 is a sectional view showing the 35 invention in use.

Figure 2 is a perspective view of the device.

Figure 3 is a longitudinal sectional view 40 through the outer end of the device.

Figure 4 is a view of a sleeve which the device is intended to remove or replace in a shaft.

As is well known some of the sleeves of 45 certain types of automobiles are constructed, as shown at A, in Figure 4, so that when placed in a shaft or housing, such as shown at B in Figure 1, the sleeve will expand and thus be held in place by friction and by the engagement of a tip *a* on the sleeve with 50 an opening *b* in the shaft. It is the object of my invention to provide a tool for removing such a sleeve from its shaft or housing and replacing it or another sleeve. In carrying out my invention I provide a tubular member 1 which is of a diameter slightly

less than the sleeve so that it can enter the sleeve. A cross sectional, curved strip 2 is placed in the tubular member with one end held in place by a clip 3 which is fastened to the inner wall of the member, and by a bolt 60 4 which passes through a hole in the tubular member and is fastened to the strip. A spring 5 on the bolt engages a nut 6 thereon so that the spring tends to hold the strip against an interior portion of the tubular member. The strip has a projection or key 7 having a flat outer surface and which is adapted to engage the oil hole *a'* in the sleeve when the puller is placed in the sleeve. A handle bar 8 is adapted to be passed 70 through holes 9 formed in the outer end of the tubular member to manipulate the same. A collar 10 is placed on the tubular member to form a shoulder.

From the foregoing it will be seen that 75 when the device is placed in a sleeve with the shoulder formed by the collar bearing against the outer end of the sleeve the projection or key 7 will be in a position to engage the hole *a'* when the puller is turned to bring 80 said key opposite the hole. In placing the device in the sleeve the bolt 4 is pressed inwardly so as to swing the strip 2 inwardly and thus bring the outer end of the key 7 flush with the tubular member so that this 85 key will not interfere with the insertion of the device in a sleeve. When the device has been partly inserted the bolt can be released as then the key will simply slide over the inner wall of the sleeve. When the shoulder 90 formed by the collar strikes the end of the sleeve the device is rotated until the key comes opposite the hole when the spring 5 will cause it to enter the hole. Then by giving the puller a turning movement to 95 the left and pulling on the handle the sleeve will be contracted and withdrawn from the shaft. If necessary the nuts 6 can be tightened on the bolt to lock the key in the hole though this is very seldom necessary. 100 A new sleeve can be put in place with this device by starting the sleeve in the housing, then inserting the puller and causing its key to engage the hole in the shaft and then giving the puller a turning movement 105 to the left and at the same time pushing it in by the handle until the sleeve slips into place.

This device is very strong though of 110 simple construction. It automatically

catches the sleeve and as it has but a few working parts it will last for a long time and will not get out of order.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A sleeve puller comprising a tubular member, a shoulder surrounding the same, a handle connected with the tubular member, a key carrier movably arranged within the tubular member, a key carried by said member and passing through an opening in the tubular member for engaging the oil opening in a sleeve, yieldable means for normal-

ly holding the carrier with the key projecting but permitting the carrier to be pushed inwardly to retract the key and adjustable controlling means therefor included in the yieldable means.

2. A sleeve puller comprising a tubular member, a handle connected therewith, a longitudinally extending strip within the member, a bracket for movably supporting one end of the strip, a key carried by the other end of the strip and passing through a hole in the tubular member, a bolt carried by the strip and passing through the tubular member, a spring on the bolt and a nut on the bolt for adjusting the tension of the spring.

In testimony whereof I affix my signature.

CHARLES M. WILKINS.
